BEST AVAILABLE COPY KNITTING-MACHINE.

No. 895,805.

Specification of Letters Patent.

Patented Aug. 11, 1908.

Application filed September 4, 1901. Serial No. 74,311.

To all whom it may concern:

Be it known that we, ROBERT W. SCOTT and HARRY SWINGLEHURST, both citizens of the United States, and residents of Philadelphia, Pennsylvania, have invented certain Improvements in Knitting - Machines, of which the following is a specification.

This invention relates particularly to rib knitting machines, although some of its features are applicable to plain machines as well.

The invention has for its general object the automatic control of changes in the character of the knitting, special objects of the invention being to provide for any desired variety of changes, such as tuck stitches, welts, slack courses, etc., repeated either at frequent or infrequent intervals, to render the pattern mechanism compact in form and simple in construction and operation, and to prevent accidental derangement of the cam mechanism between its successive adjustments.

In the accompanying drawings: Figure 1, is a plan view of the pattern devices, and of so much of the machine as is necessary to illustrate their application thereto; Fig. 2, is a side elevation; Fig. 3, is a sectional view on the line $x-x$ Fig. 1; Fig. 4, is a sectional view on the line $y-y$ Fig. 1; Fig. 5, is an inside view of part of the cam ring; Fig. 6, is a plan view illustrating a duplex form of the pattern mechanism; Fig. 7, is a side elevation of the same; Fig. 8, is a section on the line $z-z$ Fig. 2; Fig. 9, is a front elevation of the pattern wheel and some of the driving devices therefor. Fig. 10, is a perspective view illustrating the arrangement of driving devices employed in connection with the duplex pattern mechanism.

The bed plate 1 which carries the rotatable members of the machine is supported by housings one on each side, the one on the left hand side of the machine being shown at 2, and to this housing most of the parts comprising the present invention are attached.

The cylinder cam ring 4 is rotatably mounted in the bed plate and is provided with gear teeth intended to mesh with and be driven by a pinion on the main shaft, as usual. These and other parts constituting the knitting head may be of ordinary construction and in the case of a rib knitting machine, may be considered to be provided with cylinder and dial cam shifting devices comprising primary

and secondary levers and their connections, such as shown and described in the Letters Patent No. 681,161 granted to Louis N. D. Williams and Harry Swinglehurst, on the 20th day of August, 1901.

In machines of this class it will be understood that changes in the character of the knitting are effected by varying the throw of the needle projecting or drawing cams, or both, and in the machine shown in the Letters Patent above referred to these cams are shifted automatically by a disk or projection 90, on a vertically adjustable rod 91, such as shown by dotted lines in Fig. 7, this disk being moved into and out of the path of the levers referred to.

The present invention relates to mechanism for governing the position of said disk or its equivalent element in structures of this class, and also to a special construction of the needle projecting cams of the cylinder cam ring and to mechanism for operating the same.

Multi-feed machines are usually employed where a wide variety of stitches is desired although the use of more than a single feed is objectionable, particularly in connection with small machines, such as those for knitting hosiery and cuffs for underwear, because fabric made with more than one thread or group of threads in each course is more difficult to ravel back when it is run upon the needles of another machine, and, in the event of an imperfection occurring, it is not practicable to rewind and utilize the yarn. Moreover, in these small sized machines, the dimensions will not admit of more than two feeds and while the plain and ordinary tuck stitches can be made thereon, complicated patterns and lace effects cannot be made, for instance, the simpler patterns can be produced by making the needles tuck at one feed and clear at the other, but more elaborate patterns may make it desirable to clear at one feed and tuck at two, or to clear at two and tuck at two, and when this is to be accomplished on a multi-feed machine at least three feeds will be required in the former case and four in the latter. Then again, for hosiery purposes, it is sometimes desirable to form welts or ridges in the fabric at intervals of say one half inch throughout its entire length, and while many machines have been designed for automatically making a welt and a slack course in a ribbed web

to form a selvage at the top of the stocking leg and a slack course at the bottom for running on to the needles of a footing machine, these machines are incapable of making a series of such welts at close intervals throughout the length of the web.

It will be understood that the pattern chain or jacquard is usually made up with four different heights of link, that is to say, low links for the plain knitting, one slightly higher for the tuck course in the welt or ridge, then a number still higher for the welt courses proper, and one higher or lower yet for the slack course. It will therefore be clear that when a multiplicity of welts is to be formed in close proximity this arrangement of the links cannot be adopted, since the welt links must be repeated in the make up of the chain as often as there are welts in the stocking leg, that is to say, between the top of the same and the slack course, which, only occurring once, at the lower end of the leg, prevents the use of a short chain having a single set of welt links and which would, by making a number of turns, make a series of welts for an indefinite length of fabric.

This invention although not limited to a single feed machine is particularly valuable in connection therewith, because the controlling devices are such and are so arranged that a great variety of stitches and patterns can be produced and a series of welts in close succession can be made, together with other desirable changes in the character of the knitting the means employed being compact and easily adjusted and long and cumbersome jacquard pattern chains being dispensed with.

The housing or frame 2 is provided with a boss 6 the face of which is planed and a flanged hub 7 of comparatively large diameter is securely bolted thereto, this hub forming a bearing for the pattern wheel 8 which is mounted thereon and is retained laterally between the flange of the hub and the face of the boss on the housing. The boss 6 is of greater diameter than the hub 7, permitting the use of friction plugs 9 which are seated in openings extending through the housing, so that they may be pressed into contact with the side of the pattern drum outside of the periphery of the flanged hub. The friction plugs are set up or adjusted by screws 9^a each provided with a lock nut as shown in Fig. 8.

The hub 7 is provided with openings which form bearings for the shafts 10 and 11, the shaft 10 carrying on its inner end a toothed wheel 13 for engaging with the fabric as the latter passes down from the knitting head to the takeup mechanism as is usual in machines of this class, said wheel being rotated by contact with the fabric and consequently moving at the rate of formation of the fabric. The shaft 10 also carries a gear wheel 14 lo-

cated just inside of the housing and meshing with a pinion 15 on the inner end of the shaft 11, upon the outer end of which is mounted a chain or sprocket wheel 16, all of which is shown by dotted lines in Figs. 2 and by full lines in Figs. 8 and 9.

The pattern wheel 8 has ratchet teeth 31 formed on its periphery and is driven by a pawl 17 hung to an arm 18 which is secured to a rock shaft 19 adapted to a suitable bearing on the housing and having another arm 18^a at an angle to the first as shown in Figs. 1 and 2; the arms 18 and 18^a and the shaft 19 thus constituting, in effect, a bell crank lever with a long hub uniting the two arms of the lever.

A lever 20 is pivoted on a stud 21 secured to the housing at the front of the machine, and said lever carries a roller 22 (Fig. 3) which bears against the face of a crown cam 23 formed on the bottom of the cam ring 4, so that said cam serves to rock the shaft 19 and arm 18 and through the action of the pawl 17 gives a step by step motion to the pattern wheel.

The pattern wheel is drilled and tapped so as to receive one or more sets of screw studs 24 which act upon the foot of a lever 25 pivoted on a stud 26, a spring 27 acting to depress the lower end of the lever. The upper end of the lever acts upon certain stitch-cam controlling mechanism hereinafter described and it may, if desired, have an extension 28 (Fig. 7) for acting on the vertically sliding disk rod 91, or in some cases a horizontally disposed lever acting as does the extension 28, may alone be employed.

One or more of the ratchet teeth are cut away, as at 29, Fig. 2, and at 30, Fig. 7, and when the driving pawl 17 reaches such a tooth the step by step motion is suspended, because the pawl is prevented from engaging the low tooth by the front arm of a lever 32 which holds it out of action. When, however, a high link 33 on a chain 34 which is mounted on the sprocket wheel 16 acts upon the back arm of the lever 32, as said chain is moved by the action of the fabric on the wheel 13, the front arm of said lever 32 is depressed and the driving pawl again gives motion to the pattern wheel until the latter is again arrested by the restored lever 32, on the arrival of another low tooth, or, as shown in Fig. 2, where only one tooth is used, when the pattern wheel has made one complete turn. These devices for arresting the movement of the pattern wheel are substantially similar to those set forth in the Letters Patent of Louis N. D. Williams, No. 646,336, dated March 27th 1900.

By this arrangement it will be clear that the pattern wheel may be used to perform a series of different functions within its circumferential scope and be arrested when one cycle has been completed, and that these cycles can be repeated.

at any desired intervals, governed only by the length of the chain 34 or the distance between the links thereof, or by dividing the pattern wheel into sections by a series of low 5 teeth, a period of rest of any desired duration may ensue between each performance of the pattern wheel.

In Figs. 6, 7 and 10 is shown an arrangement of the mechanism whereby a still 10 greater scope of performance is possible. In this case the flanged hub 7 carries a number of pattern wheels, two being shown, and these are actuated by two pawls 35 and 36 driven in common in the same manner as the 15 pawl 17.

The pawl 35, which drives the outer ratchet wheel 37, is controlled as to its active or inactive position, by a lever 38 which is acted upon by the links of the outside chain 39 and 20 is raised as at 40 to bridge over the inner chain 41, the top face of the inner end of this lever lying under the pawl 35 so that when the lever is raised by a high link the pawl is 25 raised too high to engage a low tooth but when a low link occurs motion is again imparted to the wheel. A lever 42 is hung on the same pivot as the lever 38 and is secured to or cast in one piece with an arm 43, that 30 is to say, they are both secured to the same hub 44. The forward end of this lever plays freely under the bridged end of the lever 38 so that when it is raised by the links of the chain 41 the arm 43 which lies under the pawl 36 raises it from engagement with the low 35 teeth of the inner ratchet wheel 45.

By the use of a multiplicity of pattern wheels as shown the field of performance of the machine is materially enlarged. For instance, in the arrangement as shown, each of 40 the pattern wheels may act upon a lever such as the lever extension 28, and each may perform a series of functions, thus one may cause the formation of a welt or a series of welts for a finish to the top of a stocking, the introduction of a splicing thread at the knee, and again above the heel and finally a slack course at or near the end of the web, and the other may have its complement of pins so arranged as to form a series of welts or tuck 45 courses or other changes in the character of the knitting, at very close intervals, either for ornamental or useful purposes, or it may, as shown in Fig. 7, be arranged to act in conjunction with a lever 25 to operate cam shifting mechanism now about to be described, and the effect produced by the shifting of the cam may be discontinued at will by arresting the wheel in either of the ways shown. In 50 multi-feed machines, moreover, each feed, or 55 rather the cam shifting devices operating in conjunction with each feed, may be controlled by a separate pattern wheel and by this arrangement the possible combinations are innumerable.

65 Journalled in a removable section of the

cam ring 4 is a shaft 50 having secured to its inner end a double acting cam 51 (Figs. 3 and 5) and on its outer end is arranged a tappet wheel or series of radiating arms 52. The needle raising cam 53 of the cam ring has a movable crest 54 secured by a rivet 55 to a slide 56 free to move vertically in the cam ring, said slide having secured to it, near its upper end, a stud 57 which is forced into contact with the cam 51 by the action of a coiled spring 58 contained in an opening in the cam ring, and retained therein by the cap plate 59, as shown in Fig. 3. If the cam 51 is a grooved cam acting positively upon the stud 57 in both directions the use of the spring 58 may be dispensed with. Intermittent motion to the extent of a quarter turn imparted to the shaft 50 has the effect of raising and depressing the crest 54 of the cam 53 and in consequence governing the throw of the needles actuated thereby so as to cause them to either tuck or clear, and where, two forms of needles are employed, for instance, some with long and some with short latches, the needles with long latches, may be caused to tuck while those with short latches are permitted to clear or cast their stitches, and by properly arranging the long and short latch needles in series, lace effects may be produced.

The wheel 52, as shown, has four arms, and these are divided into pairs, those in diametric opposition constituting a pair and one pair 75 being in a different circumferential plane from the other pair 76. On top of the bed plate 1 and secured thereto by screws 60 is an annular plate 61 over which the flat ends of the arms of the wheel 52 pass either in contact or in such close proximity, that during such passage the wheel can not turn. The plate 61, however, is undercut at 62 for the reception of a dovetailed slide 63, which carries a projecting pin 64, and, immediately under this pin, the slide 63 is recessed or hollowed out, as at 65, while inwardly beyond this recess a narrow ledge 66 is left the full thickness of the plate 61. A stud 67 is secured to and projects upwardly from the slide 63 and this stud enters a slot 68 in the end of a lever 69, pivoted by a screw stud 70 to the bed plate, the other end of said lever 69 having a slot 71 which receives a stud 72 at the top of the lever 25, so that when said lever is rocked on its pivot as already described, the slide 63, together with the pin 64, are moved in and out or towards and from the center of the machine.

When the slide and its pin 64 are thrown to the innermost position the arms of the wheel 52, rotating with the cam ring, come into contact successively with the pin, whereupon the wheel is, in the present instance, given a quarter turn for each such contact, the recess 65 permitting the movement but the annular plate 61 preventing

such movement at any other point in the rotation of the cam ring. Assuming that the stud 57 has been on the lower portion of the cam 51, then the cam crest 54 has been in the lowermost position, and upon the wheel being turned it has been raised to the uppermost position, and, if the pin 64 is permitted to remain in the projected position, a quarter turn will be imparted to the wheel at each revolution of the head and the needles will be fully projected for one course and only partially projected on the next course.

It will be observed that it will be impossible for the cam 51 to turn except at the one spot and then only when the pin 64 is in active position, for when it is retracted the ledge 66 which is of the full thickness of the plate 61, fills up the inner portion of the recess in the plate and the latter thus constitutes a continuous annular lock for the wheel 52, hence it is impossible for the wheel to move out of time, moreover when the pin 64 is withdrawn from the projected position the movement is not, at first, carried beyond the point where the pin would act on the arms 75 of the wheel 52 which are in a plane outside of the other pair of arms 76, hence, if, for any reason, the withdrawal of the pin 64 should occur when the crest of the needle cam was in the depressed position and a continuance of the knitting would result in the work loading up on the needles, this condition could not continue, for the relation between the double cam 51 and the arms 75 of the wheel 52 is such that when one of said arms is struck by the pin 64 the crest of the needle cam must be left in the fully projected or knitting position.

It will be evident that by using a wheel with more arms and by modifying the cam to suit, many variations of stitches may be produced, even when the pin 64 is permitted to remain in action, and by withdrawing the pin for a few courses and permitting it to remain in for a few courses other variations may be secured, and in some cases all of the arms of the wheel may be in the same plane.

Apart from the functional advantages of the controlling devices described herein they possess merit from a structural and economic point of view, for instance, all or nearly all of the movements are pivotal in character, which admittedly permits of cheaper construction than where sliding movements are employed, and the disposition or location of the shafts 10 and 11 within the bearing of the pattern wheel, thus making them eccentric to its center, permits of the placing of the pattern wheel at a point sufficiently low to render possible the use of vibrating driving devices and connections over the wheel, and by throwing the center of the pattern wheel well to the rear of the center of the machine the back part of its rim is thrown clear of the housing so that ready access can be had to

the screw studs which may have to be frequently re-arranged. Then again, when it becomes necessary to use larger pattern wheels the same sized gearing, chain wheel and fabric wheel are employed, and the centers remain precisely the same, moreover, as the chain wheel is not lowered when the pattern wheel is increased in size, the chain carried thereby may be kept full length without coming into contact with the floor.

It will be understood that the cam shifting mechanism herein described may work in conjunction with the dial needle cams either by acting thereon direct when secured to the dial cam cap or it may be carried by the cam ring as herein shown and by the use of suitable connections still serve to shift the dial needle cams. It may also be employed to shift the retracting cams instead of the projecting cams as shown.

The term "pattern wheel" as used in the claims is intended to cover either a patterning wheel such for instance as shown in the drawings or a wheel carrying a pattern chain such as may sometime be used in place of a patterning wheel.

Having thus described our invention, we claim and desire to secure by Letters Patent:

1. In patterning mechanism for knitting machines, the combination of the pattern wheel, means for operating the same, and a secondary pattern device controlling such operation and having a spindle passing through the hub of the pattern wheel and eccentric in respect to the axis of the pattern wheel, substantially as specified.

2. The combination in patterning mechanism for knitting machines, of a pattern wheel, means for operating the same, and controlling devices therefor having as an element a wheel engaged and turned by the fabric passing from the machine, said wheel having a spindle passing through the hub of the pattern wheel and eccentric in respect to the axis of the same, substantially as specified.

3. In patterning mechanism for knitting machines, the combination of the pattern wheel, means for operating the same, and controlling devices therefor having as elements a wheel engaged and turned by the fabric passing from the machine and having a spindle passing through the hub of the pattern wheel, a secondary pattern device also having a spindle passing through the hub of the pattern wheel, and gearing connecting said spindles, substantially as specified.

4. In patterning mechanism for knitting machines, the combination of a pattern wheel and means for operating the same, a secondary patterning device controlling such operation, and a hub detachably secured to the frame of the machine, said hub presenting a periphery which constitutes a bearing for said pattern wheel and having an opening

- which constitutes a bearing for the shaft of said secondary patterning device, substantially as specified.
5. The combination in patterning mechanism for knitting machines, of a pattern wheel, and actuating mechanism therefor having as one of its elements, a vibrating pawl carrying lever having its axis between the pattern-wheel and the bed of the machine, and a secondary pattern device controlling the operation of the pawl, and having a spindle passing through the hub of the pattern wheel and eccentric in respect to the axis of the same substantially as specified.
- 15 6. In patterning mechanism for knitting machines, the combination of a pattern wheel with operating mechanism therefor having as elements a bell crank lever mounted upon a pivotal axis located between the pattern wheel and the bed of the machine and carrying a pawl engaging with a ratchet wheel connected to the pattern wheel a lever engaging with said bell crank lever and having an antifriction roller engaged by a cam on a rotating element of the machine, and a secondary pattern device controlling the operation of the pawl, and having a spindle passing through the hub of the pattern wheel and eccentric in respect to the axis of the same substantially as specified.
- 25 7. The combination in a circular knitting machine, of the cylinder and dial cam operating devices, the series of pattern wheels for actuating the same, independent mechanism for operating each pattern wheel and mechanism whereby each wheel can be started and stopped independently of the other wheel or wheels of the series, substantially as specified.
- 40 8. The combination in a circular knitting machine, of the cylinder and dial cam operating devices, a series of pattern wheels for actuating the same, a driving device common to all the wheels of the series but having an independent driving element for each wheel, and provision for throwing either of said driving elements out of action independently, substantially as specified.
- 50 9. The combination in patterning mechanism for knitting machines, of a series of pattern wheels, a driving device common to all of the wheels of the series but having an independent driving element for each wheel, and provision for throwing either of said driving elements out of action independently or permitting them to remain in action simultaneously, substantially as specified.
- 55 10. The combination in patterning mechanism for knitting machines, of a series of pattern wheels disposed side by side, a driving device having an operating pawl for each wheel, a secondary patterning device, and pawl lifters, one for each operating pawl, said pawl lifters being capable of independent operation by said secondary patterning device, substantially as specified.
11. Cam adjusting mechanism for knitting machines having as elements a shaft with projecting arms thereon, a device for engaging the said arms to cause partial turning movement of the shaft, means for moving said engaging device into and out of operative position, and a plate for locking the arms of the shaft in position between their movements, substantially as specified.
- 15 12. Cam adjusting mechanism for knitting machines having as elements a shaft with projecting arms thereon, means for locking said arms in position between their movements, a device for engaging with the arms to turn the shaft, means for moving said engaging device into and out of operative position, and a lock movable with the engaging device and serving to prevent rotation of the shaft when said engaging device is out of operative position, substantially as specified.
- 20 13. Cam adjusting mechanism for knitting machines having as elements a shaft with arms thereon, a locking plate acting on said arms to prevent rotation of the shaft, said plate having a gap to permit rotation of the shaft, and a device in line with said gap in the plate and movable into and out of engagement with the arms to turn the shaft, substantially as specified.
- 25 14. Cam adjusting mechanism for knitting machines having as elements a shaft with projecting arms thereon, a plate for engagement with said arms to prevent turning of the shaft, said plate having a gap therein, a device in line with the gap for engaging with the arms to turn the shaft, said device being movable into and out of operative position, and a supplementary lock also in line with the gap in the locking plate and movable with the turning device to lock the arms when said turning device is out of operative position, substantially as specified.
- 30 15. Needle cam adjusting mechanism for knitting machines having as elements a shaft with projecting arms thereon, a device movable into and out of engagement with said arms to turn the shaft, and operating mechanism for said device under control of a pattern surface, said parts being so disposed that the turning device, immediately before becoming inoperative, will move the needle cam to the projected position, substantially as specified.
- 35 16. In cam adjusting devices for knitting machines, the combination of the movable section of the knitting cam, a slide carrying the same and having a projection thereon, an adjusting cam acting on said projection, and means for intermittently moving the adjusting cam and locking it between its movements, substantially as specified.
- 40 17. In cam adjusting devices for knitting machines, the combination of the movable section of the knitting cam, a slide carrying the same and having a projection thereon,

an adjusting cam acting on said projection, resilient means for moving the slide in opposition to the action of the adjusting cam, and means for intermittently moving the adjusting cam and locking it between its movements, substantially as specified.

In testimony whereof, we have signed our

names to this specification, in the presence of two subscribing witnesses.
